UNITED STATES PATENT OFFICE.

JOHN E. WRIGHT AND JOHN P. SMITH, OF SEATTLE, WASHINGTON.

CANNERY EXHAUST-BOX.

1,079,819.

Specification of Letters Patent. Patented Nov. 25, 1913.

Application filed February 7, 1912. Serial No. 676,105.

To all whom it may concern:

Be it known that we, JOHN E. WRIGHT and JOHN P. SMITH, citizens of the United States, residing at Seattle, in the county of King and State of Washington, have invented certain new and useful Improvements in Cannery Exhaust-Boxes; and we do hereby declare the following to be a full, clear, and exact description of the invention, such as will enable others skilled in the art to which it appertains to make and use the same.

This invention relates to exhaust boxes for canneries and has for an object to provide a structure adapted to transport filled cans of goods through a heated chamber for the purpose of sterilizing or cooking the contents of the cans.

A further object of the invention is to provide an improved structure for transporting cans through a heated chamber backwardly and forwardly in a zigzag line to finally discharge the can at the corner of the chamber opposite its point of introduction.

A further object of the invention is to provide improved mechanism for carrying out the aforesaid objects.

A further object of the invention is to provide improved means for heating the chamber through which the cans are transported.

A further object of the invention is to provide improved means for reversing the direction of the cans at each end of the heated chamber.

With these and other objects in view the invention comprises certain novel constructions, combinations and arrangements of parts as will be hereinafter more fully described and claimed.

In the drawings:—Figure 1 is a top plan view of the device, parts of the ends of the cover being broken away to show the structure beneath. Fig. 2 is a view of the device in side elevation. Fig. 3 is a fragmentary enlarged top plan view of the mechanism for reversing the direction of movement of

the cans. Fig. 4 is a top plan view of the heating coils showing other detail of the structure in horizontal section. Fig. 5 is a detail view of the device for reversing the direction of movement of the cans.

Like characters of reference indicate corresponding parts throughout the several views.

The improved exhaust box which forms the subject matter of this application comprises a chamber 10 composed of side walls 11, end walls 12, bottom 13 and a removable top closure 14. The top closure is maintained upon the chamber in a substantially steam tight condition in any approved manner as by the employment of fingers 15 secured to such cover and with eccentric locks 16 pivotally secured by the links 17 to the side walls 11.

Within the chamber 10 and spaced above the bottom 13 are a plurality of T-irons 18 extending longitudinally of the chamber 70 throughout its entire length with other T-irons 19 disposed between the T-irons 18 and stopping short of the ends, as will be hereinafter more fully described. Between the T-irons 18 and 19 channel irons 20 are 75 located in the channel of which cables 21 are mounted to move, such cables passing over sheaves 22 and 23 carried at one end of the chamber upon shaft 24 and at the opposite end of the chamber over sheaves 25 and 26 80 carried upon the shaft 27. The sheaves 22 at one end and 25 at the opposite end are carried rigidly upon the shafts 24 and 27 respectively while the sheaves 23 at one end and 26 at the opposite end are free to rotate 85 upon the shafts 24 and 27 respectively. The shaft 24 is driven by any approved gearing as shown at 28 and from a pulley 29 being substantially the usual and ordinary form of driving such apparatus. The shaft 27 is 90 driven from the shaft 24 by employing a sheave 30 upon the shaft 24 and a sheave 31 upon the shaft 27 with a crossed cable 32 connecting the two sheaves. It is therefore apparent that the two shafts 24 and 27 are 95 driven in opposite directions so that the

cables which pass over the tight sheaves upon both of such shafts will move in opposite directions as indicated by the small arrows at the left of Fig. 1.

- 5 To facilitate the proper introduction of cans to the chamber one of the cables 33 extends outwardly beyond the shaft 24 and passes over a sheave 34 journaled upon a shaft 35 and receiving power and motion 10 from the shaft 27. To discharge the cans from the chamber a like cable 36 extends beyond the shaft 27 over a sheave 37 and the cable receives motion from the shaft 24. It will be noted especially from Fig. 5 that 15 the cables extend upwardly above the flanges of the channels 20 and also above the flanges of the T-irons 18 and 19. By this arrangement a can which is shown in dotted lines at 38 in such Fig. 5 would rest upon the top of 20 the cable 20 and only slightly upon either one of the other flanges of the T-irons 18 and 19 so that as the cables move longitudinally of the chamber the cans resting upon such cable will be moved also there- 25 with.

To reverse the direction of movement of the cans at the opposite ends of the chamber disks 39 are employed carried upon the upper ends of shafts 40 which extend 30 upwardly through the bottom 13 of the chamber and are journaled in bearings 41. Under the bottom of the chamber the shafts 40 are provided with bevel gears 42 inter- 35 geared with gears 43 carried upon the shafts 44, the shafts being similar at each end of the chamber. The shafts 44 are driven by means of sprockets 45 and sprocket chains 46 from sprockets 47 and 48 carried upon shafts 24 and 27 respectively. The disks 40 39 are chamfered at their peripheries so that the cans 38 carried along upon the cables will be moved readily upon the disks and the disks being rotated as indicated in Fig. 3 will move the cans about the 45 extremities of the T-irons 19 which extend over the disks substantially to the centers thereof and discharge them between the adjacent T-irons as indicated at Fig. 3 so that the direction of such cans will be reversed 50 to travel to the opposite end of the chamber.

To heat the chamber a coil of pipe 49 is located in the chamber having inlet and outlet connections 50 and 51. It is necessary that the cans being transported through 55 the heated chamber be maintained in a moist condition to prevent the contents of the can from sticking to the inner surface of the cans. For this purpose pipes 52 extend longitudinally of the chamber, perforated to 60 permit the escape of steam and connected independently to laterals 53 which in turn connect with a supply pipe 54 and controlled by independent valves 55. To maintain the cables 21 in taut condition, heavy

sheaves 56 are journaled upon arms 57 which 65 are fulcrumed at any convenient point upon the under side of the chamber and bear upon such cables.

In operation it will be apparent that cans will be set upon the cable 33 at the lower 70 left hand corner in Fig. 1 between the adjacent T-irons and by such cable will be moved into the chamber and longitudinally of such chamber to the opposite end where it will be discharged upon the disk 39 and 75 its direction changed. To provide a proper rotation of the can upon the disk a scalloped member 58 is secured at each end, the utility of such strip being shown best at Fig. 3. As the cans are rotated upon 80 the disk 39 in engagement with such scalloped member 58 they are discharged upon the oppositely traveling cable and are moved to the opposite end of the chamber where their direction of travel is again reversed. 85

It will be apparent that the cans will travel backwardly and forwardly through the chamber until finally discharged upon the cable 36 which will move them out of the chamber at the upper right-hand corner 90 of Fig. 1 where they may be removed from the cable and sealed.

We claim:—

1. In a device of the class described, a chamber, channels extending longitudinally 95 of the chamber in spaced relation, cables disposed in the channels, means to move alternate cables in opposite directions, guides disposed upon opposite sides of the channel, and means at opposite ends of the chamber adapted to move an object from one cable to the oppositely traveling adjacent cable. 100

2. In a device of the class described, a housing, channels extending longitudinally 105 of the housing, cables moving in the channels, alternate cables moving in opposite directions, said cables extending slightly above the flanges of the channel, guides positioned upon opposite sides of each of the 110 channels, and means to transfer an object from one cable to the adjacent cable at the completion of travel of said object upon said cable.

3. In a device of the class described, a 115 plurality of channels, sheaves journaled at the ends of said channels, cables carried upon the sheaves and moving in the channels, alternate cables moving in opposite directions, the extreme cables extending beyond the remaining cables, guides positioned upon opposite sides of the channels and proportioned to support an object upon the cable, and means at opposite ends of the channels for moving the object laterally 120 from one cable to the next.

4. In a device of the class described, a housing having cables extending longi-

tudinally thereof and moved alternately in opposite directions, disks mounted to rotate in horizontal planes located immediately above the cables, the edges of said 5 disks being tapered substantially to an edge, the opposite sides of said disks moving in the direction of the cable adjacent which it occurs.

In testimony whereof we affix our signatures in presence of two witnesses.

JOHN E. WRIGHT.
JOHN P. SMITH.
